PIPE LAYOUT TOOL

Opie P. Parsons, Charleston, W. Va.

Application February 21, 1946, Serial No. 649,274

5 Claims. (Cl. 33—175)

1

This invention relates to pipe lay-out tools, and more particularly to such a tool adapted for the marking of and forming patterns for non-planar intersections of piping and similar devices.

A primary object of the invention is the provision of an improved tool which may be utilized for the lay-out of appropriate apertures in piping or the like, and from which a pattern for the shape of an intersecting pipe may be readily made.

An additional object of the invention is the provision of such a device which may be utilized for a relatively large variety of sizes of pipes without material adjustment thereof.

A still further object of the invention is the provision of such a device including a plurality of adjustable rods, and means whereby the spreading of the rods in the use of the device is substantially precluded.

Still another object of the invention is the provision of such a device having an integral protractor and level, whereby accuracy of alignment is assured.

A still further object of the device is the provision of a centering pin, whereby absolute accuracy of the work performed on, is thereby substantially assured.

Still other objects reside in the provision of such a device which is sturdy and durable in construction, reliable and efficient in operation, and relatively simple and inexpensive to manufacture, assemble and utilize.

Other objects will in part be obvious and in part be pointed out as the description of the invention proceeds, and shown in the accompanying drawings, wherein there is disclosed a preferred embodiment of this inventive concept.

In the drawings:

Figure 1 is a side elevational view of one form of the device embodying features of this invention shown as applied to a pipe to be marked, certain portions thereof being broken away.

Figure 2 is a top plan view of the device disclosed in Figure 1, certain portions thereof being omitted.

Figure 3 is a fragmentary view illustrating a phase in the operation of the device.

Figure 4 is a fragmentary elevational view showing the application of a pattern formed on the device to a section of pipe to be cut.

Similar reference characters refer to similar parts throughout the several views of the drawings.

Having reference now to the drawings, the device of the instant invention is comprised of a

2

plurality of parallel discs 10, 11, 12, 13 and 14. The discs are secured in related assembly, as by tie bolts 15, provided with heads 16, and secured in position, as by nuts 17. Spacer sleeves 18 are provided between discs 13 and 14, and additional spacer sleeves 19 are provided between discs 12 and 13 to assure the relative fixed related assembly of the parts. Further spacer sleeves 20 are provided between discs 10 and 12, the disc 11 being mounted, as by means of suitable arcuate slots (not shown) for relatively slight rotation with respect to the other discs for a purpose to be more fully described hereinafter.

Aligned centrally disposed apertures in each disc accommodate a sleeve 25 interiorly threaded, as at 26, through which extends a rod 27 terminating, as at 28, in a centering pin for the apparatus. The rod 27 may be provided with a suitable traveler nut, whereby rotation of a nut 29 at the upper extremities thereof beyond the plate 10 serves to move the point 28 to a desired location, in accordance with the setting of the device.

Referring now to Figure 2, it will be seen that each of the discs 10 to 14, inclusive, is provided with a plurality of concentric circles of spaced apertures, each of the circles being of a different diameter, the innermost circle being comprised of a plurality of apertures 30 surrounded concentrically by circles of apertures 31, 32, 33 and 34, each defining a circle of a different diameter in conformity to a conventional pipe size. It is to be noted that the axial rows of apertures as defined by the dotted lines A—A and B—B (see Fig. 2) are located at an angle of exactly 90° with respect to each other to facilitate the accurate location of the parts laid out during assembly. In accordance with the diameter of the pipe to be fitted, rods 35 terminating in pointed tips 36 are inserted in each aperture of the appropriate circle and adjusted in a manner to be more fully described hereinafter.

The uppermost disc 10 and the lowermost disc 14 are each provided with a laterally extending projection 37 and 38, respectively, between which projections is secured a supporting frame 39 carrying a protractor 40 provided with a conventional level 41, whereby accurate setting of the device in any desired angle is assured. Suitable screws 42, as best shown in Figure 2, may be employed to secure the frame 39 in appropriate position. An adjusting screw 43 is similarly provided for suitable adjustment of the protractor.

As best shown in Figure 1, a supporting member is provided for the device and comprises a tubular member 50 terminating at its upper end

in a bifurcated portion 51 comprising strips pivotally secured, as by nuts 52, to pivots 53 secured to reinforcing members 54 carried by the uppermost disc 10. The tubular member 50 is bent or inclined at an appropriate angle, as best seen in Figure 1, and contains a slidably mounted second tubular member 55 telescopically therein, the position of which and the adjustment of which may be determined by a set screw 56 mounted in a suitable bushing 57 in the side of tubular member 50. Tubular member 55 is correspondingly provided with a bushing 58 and a set screw 59, and in turn has a rod 60 telescoped therein, the lower end of which terminates in a point 61 which comprises the extremity of the support. It will thus be seen that a relatively wide adjustment both of the position and the length of the support may be readily accomplished in accordance with the positioning of the device on the pipe to be operated upon.

Referring now to the means for locking the rods 35 in adjusted positions, the purpose of which will be more fully pointed out hereinafter, each of the discs 10 and 12 is provided with a laterally extending portion 65 and 66, respectively, to which are secured the legs 67 and 68, respectively, of a clamping bracket 69, provided with a centrally disposed threaded aperture in alignment with the disc 11 through which passes a locking screw 70. The extremity of the locking screw 70 is adapted to abut an extending portion 71 of the disc 11, in such manner that rotation of the locking screw 70 serves to rotate the disc 11, by virtue of the arcuate slots 11' previously described, and cause the apertures of the appropriate row therein to bear tightly against the sides of the rods 35, thus holding the rods securely in aligned position against displacement.

The upper portion of the projection 65 is provided with a pair of upstanding lugs 75 and 76, respectively, between which is mounted a conventional level 77 carried by a pin 78 extending through suitable apertures in the lugs 75 and 76, and held in position, as by a spring 79. The level 77 includes a longitudinal level 77a and a cross level 77b. The purpose of the level 77 is to permit the accurate alignment of the device with a pipe or any suitable surface while setting up for the pattern to be cut in a manner to be described hereinafter. The level 77 is mounted on the disc 11 radially thereof and of the centering pin sleeve 25. This arrangement positions the cross level 77b on a radial plane of the disc 11 and the longitudinal level 77a in a plane parallel to a plane tangential to the disc 11. Also, the cross level 77b is in alignment with the transverse center line defined by the radial row of apertures A—A. The level 77 is adapted to be turned on its pins 78 whereby to level the longitudinal level 77a. Leveling of the cross level 77b is accomplished by rotating the assembly of discs with the centering pin 28 as an axis.

Referring now to Figure 1, the operation of the device for laying out an opening in a horizontal pipe or workpiece 80 comprises setting the protractor 40 at the angle at which the branch pipe is to extend from the main pipe 89 and locking said protractor by means of the screw 43. The centering pin 28 is now applied to the workpiece at the center point of the desired opening in the workpiece 80. A coarse adjustment of the support 50 is now made by means of the thumb screw 56 and the telescoped tube 55. At the same time the thumb screw 59 for the fine adjustment rod 60 is now loosened. Meanwhile, the rods 35 may

be retracted or at least held loosely in the assembly of discs. It is understood moreover, that the rods 35 have been inserted in a circle appropriate to the diameter of the branch pipe to be applied to the main pipe 80. The assembled tool is now rotated on the axis of the centering pin 28 until the cross level 77b registers level. During this operation the fine adjusting point 61 of the fine adjusting rod 60 is in engagement with the work and when the cross level 77b registers level such point 61 will be longitudinally aligned with the centering pin 28 on the center line of the workpiece 80. The assembled tool is now raised or lowered until the protractor level 41 registers level. At this time the fine adjustment thumb screw 59 may be tightened to lock the support 50 in proper angular relation to the workpiece 80. At this time, also, the level 77 may be rotated on the pin 78 to level the longitudinal level 77a. Obviously, the longitudinal level 77a will agree with the level 41 of the protractor 40. However, by providing a longitudinal and cross level together, the operator can readily reset the tool on a workpiece 80 at the proper angle and with the pins 28 and 61 in longitudinal alignment with the center line of the workpiece without referring again to the level 41 of the protractor. This is an obvious advantage when a plurality of openings must be cut in a workpiece 80 at the same vertical angle relative thereto. The rods 35 are now projected into engagement with the surface of the workpiece 80 and locked by means of the thumb screw 70.

After all the points 36 have been arranged in point contact with the surface of the pipe 80, the locking screw 70 is turned, rotating the plate 11, and securely fixing the rod in position to mark the aperture to be cut. Chalk or other suitable material may then be utilized to draw a line 81 extending about the space defined by the circle of points 36. This aperture may then be cut out and is ready for the application of the intersecting pipe thereto. The device is then removed from the pipe, and a paper pattern 82, as best shown in Figure 3, is positioned around the point and suitably cut to conform to the circle defined by the plurality of points. The paper 82 may be held in place, as by a rubber band 83, a string, or similar device. After the pattern has been cut, it will be readily understood that it may be removed, and, as best shown in Figure 4, applied about the pipe to be fitted 85, whereupon the pipe 85 may be suitably cut in accordance with the pattern, thus insuring a fit of extreme accuracy between the aperture cut in the pipe 80 and the fitted pipe 85.

Obviously, a relatively great adjustment of angles, sizes and fittings may be provided by suitable adjustment of the apparatus. Similarly the device may be advantageously utilized for the layout of pipe intersections with vessel surfaces, such as branches or openings in tanks or for the layout of the intersection of the components of vessels, such as domes on boilers or the like.

From the foregoing it will now be seen that there is herein provided an improved device of the character described which accomplishes all the objects of this invention, and others, including many advantages of great practical utility and commercial importance.

As many embodiments may be made of this inventive concept, and as many modifications may be made of the embodiment hereinbefore shown and described, it is to be understood that all mat-

ter herein is to be interpreted merely as illustrative and not in a limiting sense.

I claim:

1. In a pipe layout tool, the combination with a plurality of rods, mounting means mounting said rods to define a circle, said rods being individually and longitudinally adjustable in said mounting means, and locking means for locking all of said rods in adjusted positions; of a work piece engaging centering pin carried by said first named means axially of said rods, means for adjusting said centering pin longitudinally independently of said rods, levelling means carried by said mounting means, said levelling means including a first level and a second level, said first level being adjustable to level the same when said centering pin is engaged with a work piece at a predetermined angle, and said second level extending radially of said centering pin and being adapted to be leveled by rotation of said mounting means.

2. In a pipe layout tool, the combination with a plurality of rods, mounting means mounting said rods to define a circle, said rods being individually and longitudinally adjustable in said mounting means, and locking means for locking all of said rods in adjusted positions; of a work piece engaging centering pin carried by said first named means axially of said rods, means for adjusting said centering pin longitudinally independently of said rods, levelling means carried by said mounting means, said levelling means including a first level and a second level, said first level being adjustable to level the same when said centering pin is engaged with a work piece at a predetermined angle, said second level extending radially of said centering pin and being adapted to be leveled by rotation of said mounting means, a work piece engaging supporting member carried by said mounting means and positioned in aligned relation with said centering pin at right angles to the plane of said second level, and said supporting member being longitudinally adjustable.

3. In a pipe layout tool, the combination with a plurality of rods, mounting means mounting said rods to define a circle, said rods being individually and longitudinally adjustable in said mounting means, and locking means for locking all of said rods in adjusted positions; of a work piece engaging centering pin carried by said first named means axially of said rods, means for adjusting said centering pin longitudinally independently of said rods, levelling means carried by said mounting means, said leveling means including a first level and a second level, said first level being adjustable to level the same when said centering pin is engaged with a work piece at a predetermined angle, said second level extending radially of said centering pin and being adapted to be leveled by rotation of said mounting means, a work piece engaging supporting member carried by said mounting means and positioned in aligned relation with said centering pin at right angles to the plane of said second level, said supporting member being longitudinally adjustable, an adjustable protractor fixed to said mounting means radially of said centering pin

whereby said pin may be engaged with a work piece at a predetermined vertical angle, and said protractor including third level cooperating with said first level and said second level.

5. In a pipe layout tool, the combination with a plurality of rods, mounting means mounting said rods to define a circle, said rods being individually and longitudinally adjustable in said mounting means, and locking means for locking all of said rods in adjusted positions; of a work piece engaging centering pin carried by said first named means, means for adjusting said centering pin longitudinally independently of said rods, a level carried by said mounting means radially of said centering pin, said level being adapted to be leveled by rotation of said mounting means, a work piece engaging supporting member, said workpiece engaging supporting member being carried by said mounting means and positioned in aligned relation with said centering pin at right angles to the plane of said level, and said supporting member being longitudinally adjustable.

20. In a pipe layout tool, the combination with a plurality of rods, mounting means mounting said rods to define a circle, said rods being individually and longitudinally adjustable in said mounting means, and locking means for locking all of said rods in adjusted positions; of a work piece engaging centering pin carried by said first named means axially of said rods, means for adjusting said centering pin longitudinally independently of said rods, a first level carried by said mounting means radially of said centering pin, said first level being adapted to be leveled by rotation of said mounting means, a work piece engaging supporting member, said work piece engaging supporting member being carried by said mounting means and positioned in aligned relation with said centering pin at right angles to the plane of said first level, said supporting member being longitudinally adjustable, an adjustable protractor fixed to said mounting means radially of said centering pin, said protractor including second level, said protractor, levels, centering pin and supporting member comprising means for setting said tool on a work piece at a predetermined vertical angle with said centering pin and support longitudinally aligned with a center line of a work piece.
